UNITED STATES PATENT OFFICE

151,066

DESIGN FOR A DIFFUSING SHIELD FOR A TUBULAR LAMP

Richard O'Connell, New York, N. Y., assignor to The Roc Industrial Corp., New York, N. Y., a corporation of New York

Application April 26, 1947, Serial No. 138,637

Term of patent 14 years

(Cl. D48—23)

To all whom it may concern:

Be it known that I, Richard O'Connell, a citizen of the United States, residing at 1436 Lexington Avenue, New York, N. Y., in the county of New York and State of New York, have invented a new, original, and ornamental Design for a Diffusing Shield for a Tubular Lamp, of which the following is a specification, reference being had to the accompanying drawing, constituting a part thereof.

Fig. 1 is a perspective view of a diffusing shield for a tubular lamp, showing my new design.

Fig. 2 is an end view.

Fig. 3 is a side view.

The design forming the subject matter of the present invention is for a diffusing shield of indeterminate length and the design is repeated throughout this length.

I claim:

The ornamental design for a diffusing shield for a tubular lamp, substantially as shown and described.

RICHARD O'CONNELL.
